UNITED STATES PATENT OFFICE.

OTHO M. OTTE, OF JAMESTOWN, NEW YORK.

HEADLIGHT-ADJUSTER.

1,300,860.

Specification of Letters Patent. Patented Apr. 15, 1919.

Application filed June 20, 1918. Serial No. 241,049.

To all whom it may concern:

Be it known that I, OTHO M. OTTE, citizen of the United States, residing at the city of Jamestown, in the county of Chautauqua and State of New York, have invented certain new and useful Improvements in Headlight-Adjusters, of which the following, taken in connection with the accompanying drawings, is a specification.

- 10 The invention relates to supports for automobile headlights and similar devices; and the improvement consists in providing a lamp having a plurality of bracket or hinge supports for attaching the same rigidly to a frame or prop at a predetermined tilt, said brackets being adjustably complementary in their action to one another as to height, tilt and sidewise adjustment, and toward these ends said brackets are preferably reversible to lower or raise said lamp, and each have a plurality of hinging and clamping or rigid attachment points; and the invention consists in the novel features and combinations hereinafter set forth and claimed.
- 15 In the drawings, Figure 1 is a perspective view of an automobile headlight with my double complementary bracket or hinge support, the lamp being held on the same level that it may be if placed directly on the fixed forked standard; and Fig. 2 is a similar view with one of the hinged clips of the bracket turned so as to hold the lamp on a lower level in respect as compared with direct attachment to the forked support; and Fig. 3 is a perspective view of an automobile lamp directly and fixedly supported on the forked prop or standard; and Fig. 4 is a perspective view of the preferred form of forked prop for supporting the brackets. Fig. 5 is a plan view of the blank of the preferred form of the fork attaching clip of the bracket or multiple hinge support with the lug at each end and having an adjusting slot in each lug preparatory to forming into a standard receiving eye by folding the lug ends into nearly contacting relation, said lug ends being spaced sufficiently to permit the insertion of the similarly folded lug ends of the lamp attaching clip of the bracket, said lamp adjusting clip being shaped exactly the same as the stand-

ard attaching clip with the exception of a round bolt hole in the lugs instead of a slot; and Fig. 6 is a perspective view of the pintle for said lamp attaching clip, which pintle is attached within the central portion of the folded clip preferably by spot welding in order to form a hinged attachment to the lamp. Fig. 7 is a top plan view showing the complementary adjustable relation of the double hinged bracket support for the lamp, the adjustability of the lamp being shown in dotted line turned slightly to one side. Fig. 8 is an elevation of the lamp with the parts of the hinged bracket support so adjusted as to raise the level of the lamp. Fig. 9 is a detail perspective view of separated parts of the adjustable bracket support before assembling. Fig. 10 is a top plan view of the assembled multiple hinge bracket showing the construction and arrangement of the different parts shown in Fig. 7. Fig. 11 is an elevation of a slight modification of one of the clips in the hinged bracket showing longer lugs having the slots for a double bolt attachment to a correspondingly shaped clip; and Fig. 12 shows a perspective view of said modified form of the bracket hinge showing the double bolt attachment of the two parts or clips of the hinged bracket which modified form is unnecessary except for heavy lamps, the single bolt hinge giving sufficient clamping power to rigidly support the average weight lamp.

Like characters of reference refer to corresponding parts in the several views.

The numeral 15 designates the automobile lamp which is preferably arranged with projecting eye portions 16 at each side to receive therethrough the supporting upper ends 17 of the two tined standard 18 which tines have the enlargements 19 thereon to hold the lamp 15 in a fixed and non-adjusting elevation in relation to said fork.

Adjustability is given to the lamp 15 on the standard 18 by means of my reversible folding hinge or bracket or hinge bracket 20 which comprises the two double angularly shaped clips 21 and 22, each of which clips are struck up from the sheet metal as shown in Fig. 5 with a lug at each end

thereof which double lugged blank is formed into an eye 23 for clip 21 by means of a suitable folding die and is attached around the pintle or non-headed bolt 24 preferably by spot welding the looped sheet metal to the pintle 24 to form the clip 22. The pintle 24 is provided with a thread and nut on its exposed end to hingingly support the lamp thereon by insertion through the eye 16 10 on the side of the lamp 15. An adjusting slot 25 is provided in the double lug of the clip 21 and a hole 26 in the double lug of the clip 22 to receive therethrough the hinging or pivoting bolt 27 for the preferred 15 form of the bracket 20.

A second adjusting slot 28 is provided in the clips 21 and 22 in the modified form shown in Figs. 11 and 12 for supporting heavy weight lamps, an upper bolt 29 being provided through the upper slots 28 20 which firmly fastens the two modified hinged clips 21 and 22 in their adjusted position. In order to rigidly attach the clips 21 on the upper ends 17 of the standard 18 set 25 screws 30 are provided through the sheet metal eye 23, said eye being preferably strengthened by means of a spring clip 31 which is sprung into and slipped to position over about the center of the periphery 30 of the eye portion 23 of the clip 21 and preferably spot welded in said position to thereby stiffen and strengthen the eye 23 and the holding power of the threaded set screw 30. The standard 18 may be supported 35 on the frame, as shown in Fig. 2, or on any other portion of the machine.

The leaves of the folded clips 21 and 22 may be alternated by the insertion of a leaf from each clip between the leaves of the opposite clip, and when so clamped together by 40 means of the clamping bolt 27 a strong clamping attachment is given to the hinged or pivotal joint formed between said clips 21 and 22 by the bolt 27 so that a lamp 15 45 will rarely move from the adjusted position. As hereinbefore stated, however, heavy lamps are firmly held by the additional bolt 29 in the upper portion of the interrelated or hinge clips.

50 The double lugged clips may be assembled in three different forms to adjust the level of the lamp. For example, in Fig. 1 wherein the lamp is held in the same elevation which it would have if attached directly to 55 the upper end 17 of the standard 18; or the elevation of the lamp may be lowered by turning the clips as shown in Fig. 2, or may be raised by turning said clips as shown in Fig. 8. The lamp will be held firmly in the 60 adjusted position by the bolts 27 and set screws 30 or for heavy lamps by the additional bolts 29.

The complementary nature of the construction of the multiple hinge brackets is

clearly shown in the top plan view in Fig. 65 7, each of the multiple hinge brackets 20 having a pivotal point formed by the eye 23 and standard end 17 and the pintle 24 in the eye 16 on the lamp 15 for adjustment in a horizontal plane, and the bolt 27 in the hole 70 26 in slot 25 for vertical adjustment, heavy lamps having the additional bolt 29 in the slots 28. Said multiple hinge points will provide means for vertical as well as horizontal or sidewise adjustment, each of the 75 brackets 20 adapting itself to the other whenever the set screws 30 or clamping screws 27 and 29 are released sufficiently to permit of horizontal or vertical adjustment, after 80 which said set screws or bolts may be tightened thereby rendering the hinge brackets 20 rigid in their support of and relation to the lamp 15 and forked standard 18 in the pre-determined position.

The lugs on the modified form of bracket 85 shown in Figs. 11 and 12 are preferably of sufficient length to provide wide spacing between the clamping bolts 27 and 29 so that the rigidity of the holding power of the bracket for heavy lamps may not be impaired. 90

It is apparent that a single hinge bracket 95 20 might be used to support the lamp 15 without departing from my invention and allowing vertical and sidewise adjustment of the lamp, though such a support would not be as satisfactory since it could not as rigidly support the lamp. 100

I claim as new:—

1. In a lamp mounting, a two-point support, connections between the respective points of the support and points on opposite sides of the lamp and means whereby to enable the connections to be independently adjusted and fixed after adjustment so as to 105 increase or decrease the distance between the respective points of the support and said points on opposite sides of the lamp.

2. In a lamp mounting, a two-point support, connections between the respective points of the support and points on opposite sides of the lamp and means whereby to enable the connections to be independently adjusted and fixed after adjustment so as to 110 increase or decrease the distance between the respective points of the support and said points on opposite sides of the lamp, and to also allow the lamp to have pivotal movement so as to incline same to the vertical. 115

3. A lamp support comprising a lamp, a 120 standard for said lamp, and a reversible hinge bracket pivotally connected to both said standard and lamp to allow vertical and horizontal adjustment of said lamp and to permit change in the elevation of said lamp. 125

4. A lamp support comprising a lamp, a suitable standard for said lamp, and a reversible hinge composed of L-shaped clips

- 5 pivotally connecting said standard and lamp which permits vertical and sidewise adjustment of said lamp and change of elevation for the same.
- 5 5. A lamp support comprising a lamp, a suitable standard for said lamp, a reversible hinge bracket composed of L-shaped clips hinged to one another, each of said L-shaped clips comprising folded U-shaped interleaving portions, a pivot pin in one of said interleaving portions for pivotal attachment to said lamp, and the other interleaving portion having an eye to pivotally receive said standard.
- 10 15. 6. In a lamp adjuster, a two-point support, independent supporting connections between the two points of the support and opposite sides of the lamp, and means whereby to allow relative pivotal movement of the 20 lamp and extension and contraction of the connections.
- 25 7. In a lamp adjuster, a support, and extensible and contractile means between the lamp and support for supporting the lamp so as to allow sidewise adjustments of the latter and rigid securing thereof after adjustment.
- 30 8. In a lamp support, a standard, a pair of members one of which is secured at one end to the standard and the other of which is reversibly secured at one end to the lamp, and means to adjustably connect the opposite ends of said members together.
- 35 9. In a lamp support, a supporting member, a pair of reversible elements connected at one end to the lamp and member respectively, and means whereby to connect the elements to each other at their opposite ends so as to allow reversal thereof.
- 40 45. 10. In a lamp support, a supporting member, a pair of reversible elements for connecting the lamp to the member, said elements having sockets at one end and spaced interengaged parts at their opposite ends, and means to connect said parts.
- 50 55. 11. In a lamp support, a support proper, and a pair of pivotally united substantially L-shaped members one of which is connected to the lamp and the other to the support proper.
- 60 65. 12. In a lamp adjuster, a support, and extensible and contractile means between the lamp and support for supporting the lamp so as to allow sidewise adjustments of the latter and to also allow the lamp to have pivotal movement so as to incline same to the vertical.
- 70 75. 13. The combination of a lamp, a forked bracket standard having a support, separate pivotally attached connecting brackets between each of the tines of said forked bracket standard and different portions of said lamp, and means to render rigid said pivotal attachment of said connecting brackets.
- 80 85. 14. A lamp support comprising a plurality of vertically and horizontally adjustable brackets, said brackets being individually and jointly reversible. 65
- 90 95. 15. A lamp support comprising a plurality of brackets, said brackets composed of clips hinged to one another to tilt vertically and hinged to said lamp to turn horizontally in unison with one another. 70
- 100 105. 16. A lamp support comprising a forked standard, two pairs of struck up clips hinged to one another in their central portions to form two brackets which are adjustable vertically, said brackets pivotally attached to said forked standard one to each tine at one end and the other ends pivotally attached 75 to the opposite sides of the lamp to move sidewise in unison with each other.
- 110 115. 17. A lamp support comprising a bracket composed of clips struck up from sheet metal having interlapping lugs hinged to one another, a pintle on one of said clips for pivotal attachment to the lamp, the other clip having an eye for pivotal attachment on a supporting standard, and a set screw through the wall of said eye to hold said clip and 80 bracket against pivotal movement. 85
- 120 125. 18. In a lamp support, a standard, and a connection between the standard and lamp including a pair of elements having similar interengaging parts. 90
- 130 135. 19. In a lamp support, a standard, and a connection between the standard and lamp including a pair of substantially similar elements. 95
- 140 145. 20. In a lamp support, a standard and a connection between the standard and lamp composed of a pair of members pivoted together at a point between the lamp and standard. 100
- 150 155. 21. In a lamp support, a standard, and a connection between the lamp and standard composed of a pair of members having interengaged parts, one of the members being reversible. 105
- 160 165. 22. In a lamp support, a standard, and a pair of interengaging elements connecting the standard and lamp, one of the elements being engageable with the other at both the top and bottom thereof. 110
- 170 175. 23. In a lamp support, a connection between the lamp and support including a pair of members individually and jointly reversible. 115
- 180 185. 24. In a lamp adjuster, a two-point support, and independent extensible and contractile connections between the two points of the support and opposite sides of the lamp. 120
- 190 195. 25. In a lamp support, a standard, and a connection between the lamp and standard including a pair of members having interleaved portions. 125
- 200 205. 26. In a lamp support, a standard, and

a connection between the lamp and standard including a pair of members connected at their outer ends to the lamp and standard respectively and means to connect the inner ends of the members to each other at a point between the lamp and standard, one of the members being reversible.

In testimony whereof I have affixed my signature in the presence of two witnesses.

OTHO M. OTTE.
